BOAT

George E. Grenier, Lake Hopatcong, N. Y.

Application July 19, 1933, Serial No. 681,206

1 Claim. (Cl. 115—49)

This invention relates to boats and more particularly to a drive for paddle wheel boats.

The objects of the invention are (1) to eliminate a draft of the boat so that it will float in 5 six inches of water; (2) to eliminate the torque of the motor which, as is well known, is not only dangerous, but very disagreeable; (3) obtain maximum speed with minimum horse power at the same time insure smooth riding of the boat, 10 and (4) provide an efficient paddle wheel having certain features distinctly characterizing it over paddle wheels now generally in use.

The invention together with its objects and 15 advantages will be best understood from a study of the following description taken in connection with the accompanying drawings wherein is illustrated a preferred embodiment of the invention.

It is to be understood at the outset that it is 20 in no wise intended to restrict the invention to the precise details of construction, combination and arrangement of elements as herein illustrated and described, other than may be necessary to meet the requirements of the prior art and scope 25 of the appended claim.

25 In the drawings:

Figure 1 is a top plan view of a boat embodying the features of the present invention.

Figure 2 is a transverse sectional view taken substantially on the line 2—2 of Figure 1.

30 Figure 3 is an enlarged fragmentary side elevational view of the boat with certain parts broken away and shown in section.

Figure 4 is a horizontal fragmentary sectional view showing a channel to be hereinafter more 35 fully referred to.

Figure 5 is a vertical sectional view through the improved paddle wheel, and

Figure 6 is a transverse sectional view through the paddle wheel.

40 Referring to the drawings by reference numerals it will be seen that 10 indicates generally the hull of the boat, and for the most part the same may be of any suitable construction and shape, preferably corresponding in shape to the hull of speed boats as at present constructed.

The passenger compartment is indicated by reference numeral 11, and in the present instance the passenger compartment, as shown, is located 45 rearwardly of the transverse center line of the boat. Forwardly of the compartment 11 is an engine room or compartment 12, and in the present instance there are mounted within the compartment 12 two prime movers 13 extending 50 transversely of the boat. The prime movers are of well known form, such as internal combustion engines and the shafts of the engine are indicated by reference numerals 14. Prime movers 13 are so relatively arranged as to have the shaft

14 of one prime mover connected by chain and sprocket means 15 with a paddle wheel 16 provided at one side of the compartment 11, and the shaft 14 of the other prime mover similarly connected with the second paddle wheel disposed 5 at the side of the compartment 11 opposite to the first named paddle wheel.

Each propeller 16 is constructed of wood or 10 any other suitable material and comprises a hub 17 having secured thereto in any suitable manner, preferably by being integral therewith spokes 18 which at their outer ends are secured to a rim 19. In the present instance the rim 19 is channel shaped in cross section and provided 15 with a plurality of transverse partitions or vanes 20 arranged therein in line with the spokes 18 as will be clear from a study of Figures 5 and 6.

In having the rim 19 of channel formation in 20 cross section and provided with the vanes 20 pockets are formed which will serve to carry the water from forward to aft, and also substantially stop the water from running up the spokes toward the hub, thus insuring maximum propulsion power as otherwise the water running along the spokes toward the hub would offer undesirable resistance resulting in a waste of 25 power. Also, the sides of the channel provide retainers at opposite sides of the wheel which prevent slippage thereby insuring full efficiency.

Further to reduce resistance there are provided in the bottom of the boat rearwardly of the compartment 11 channels 21 arranged at opposite sides of the boat and in line with the paddle wheels 16. The bottom of the boat forming the top wall of the channels 21 are curved 30 as shown particularly in Figure 3 giving the water free passage through the channel, and eliminating, rearwardly of the paddle wheel squared or flat corner portions or surfaces 35 against which the water may strike resulting in undesirable resistance and cutting down the speed of the boat.

Having thus described my invention, what I 40 claim as new is.

A boat having in combination a hull provided 45 with a passenger compartment, and an engine compartment forwardly of the passenger compartment, a pair of prime movers mounted in the engine compartment, paddle wheels at opposite sides of the passenger compartment there being one paddle wheel for each prime mover, a driving connection between each paddle wheel and its prime mover, said driving connection being disposed exteriorly of and at opposite sides 50 of said passenger compartment, and channels in the bottom of the hull extending rearwardly from the passenger compartment in line with the paddle wheels.

GEORGE E. GRENIER.
